UNITED STATES PATENT OFFICE.

JUAN CALAFAT Y LÉON, OF MADRID, SPAIN.

APPARATUS FOR ASCERTAINING THE DEGREE OF PURITY OF AIR.

1,101,400.

Specification of Letters Patent.

Patented June 23, 1914.

Application filed February 13, 1913. Serial No. 748,147.

To all whom it may concern:

Be it known that I, JUAN CALAFAT Y LÉON, of No. 42 Calle de Fuencarral, Madrid, Spain, chemist, have invented certain new and useful Improvements in Apparatus for Ascertaining the Degree of Purity of Air, of which the following is a specification.

This invention has for its object to provide an improved apparatus to show the degree of purity or corruption of the air, according to its proportion in oxygen.

We know that the air is a gaseous mixture of oxygen, nitrogen, carbon dioxid, vapor of water and other ingredients in small quantities. The composition of the gaseous mixture just above mentioned, represents the atmosphere in a normal condition, but when the air is closed up, with its occupants in a room without exterior communication, the air will contain many ingredients detrimental to the health when breathed into the lungs. The air in such cases is rendered unfit for respiration very largely, by the exhaustion of the oxygen and the production of carbonic acid gas.

The means by which my invention is carried into effect are shown in the accompanying drawing, in which—

30 Figure 1, is an elevation, in perspective, of the device. Fig. 2 is a side elevation of a section on the line A—B, of Fig. 1. Fig. 3 is a cross section on the line C—D, of Fig. 1 and Fig. 4, is a cross section on the line

35 E—F, of Fig. 1.

The various parts of the device are referred to by letters, similar letters denoting corresponding parts in the several views.

Referring to the drawing, the letter *h* designates a metallic box or case. This case is provided with three openings having suitable covers. The lower one of said openings *d*, admits the outer air. The upper opening *e*, is in the top or cover of the case, to permit the introduction of alcohol or other suitable combustible, which saturates the filament *i* and the pumice stone *k*. The third opening *m*, connects the heating devices with the outer air.

40 A lamp *n*, is located in the projecting part of the upper end of the case *h*, and is fixed to the case by a threaded ring *o*, and when not in use, is covered with a cap *p*. This lamp *n*, is provided with a tubular gauze *r*, of very fine platinum wire held in place by a thin frame of nickel attached to the tube.

The tube *r* contains two or three globules of sponge of platinum, to initiate the ignition of the combustible vapor.

The case *h*, is divided into three parts, 60 of which the lower one constitutes a small cavity to control the inflow of the air. The middle part *h'* is the largest part, and is provided exteriorly with vertical ribs *t* with grooves between them, up which, on 65 the inside there extends a thick cloth or wick filament *i*, the central space being stuffed with raw cotton *i'*. The upper division of the casing is occupied by pieces of pumice stone contained in a tube of metal- 70 lic cloth.

V is the oximeter which I employ, having a face scale *v*. In order to graduate the oximeter it is necessary to mark a point in the scale corresponding to the highest temperature obtained by the calorific focus which is fed by pure country air and is to be considered as normal air. The other divisions of the scale are marked by placing the apparatus in a glass through which circulates slowly and in an upward direction a gaseous mixture, or artificial air, formed of pure oxygen and nitrogen, whose respective quantities in volume are measured beforehand, at will, and subject to the conditions of the normal air. In this manner is graduated an apparatus of great precision for the graduation of all the others which are being constructed for comparison with the first one using the arbitrary gaseous 80 mixtures formed by the air united to the products of the respiration.

Having now described the invention, what I claim, is—

1. An apparatus for ascertaining the proportion of oxygen present in a gaseous mixture, comprising a metal casing provided with vertical ribs, an overhanging top portion on said casing, a valve in the lower portion adapted to admit the gaseous mixture 95 to be tested, an absorbent filling in the main portion of said casing, the top portion of said casing being provided with an aperture for the introduction of a combustible liquid, a wire gauze sleeve connecting two openings 100 through which one leg of a differential thermometer passes, a threaded collar to secure said sleeve, a heating device surrounding the bulb on said leg of said thermometer, said heating device being open at both ends and provided with a wire gauze member and with means chemically adapted to cause 105 110 115

combination of oxygen with the combustible gas or vapor, the other leg of said thermometer being exposed to the action of the atmosphere.

5. 2. Apparatus for ascertaining the proportion of oxygen present in a gaseous mixture comprising a metal casing provided with vertical ribs, an overhanging top portion on said casing, a valve in the lower portion 10 adapted to admit the gaseous mixture to be tested, an absorbent filling in the main portion of said casing, the top portion of said casing being provided with an aperture for the introduction of a combustible liquid, a 15 wire gauze sleeve connecting two openings through which one leg of a differential thermometer passes, a threaded collar securing said sleeve, a heating device surrounding

the bulb on said leg of said thermometer, the heating device being open at both ends 20 and provided with a wire gauze and with means chemically adapted to cause the combination of oxygen with the combustible vapor, the other leg of said thermometer 25 being exposed to the action of the atmosphere, and a graduated scale for indicating the relative differences in temperature produced, or the percentage of oxygen in the gaseous mixture.

In witness whereof I have hereunto set 30 my hand in the presence of two witnesses.

JUAN CALAFAT y LÉON.
